UNITED STATES PATENT OFFICE.

FRANK W. EAGELSTON, OF BERKELEY, CALIFORNIA.

TRAVELING BRIDGE CRANE.

Application filed January 1, 1923. Serial No. 610,084.

To all whom it may concern:

Be it known that I, FRANK W. EAGELSTON, a citizen of the United States, and a resident of Berkeley, in the county of Alameda and State of California, have invented a new and useful Improvement in Traveling Bridge Cranes, of which the following is a full, clear, and exact description.

My invention relates to improvements in process and means for switching railroad cars, and it consists in the steps hereinafter disclosed, and in the combinations, constructions, and arrangements herein described and claimed.

15 An object of my invention is to provide a traveling crane which will quickly and with safety pick up and set down a railroad car or other standard shaped object.

20 A further object of my invention is to provide a crane for picking up and setting down a railroad car which will cause no undue or dangerously abnormal strain or pressure to be brought upon a car or any of its parts.

25 A further object of my invention is to provide a crane for picking up and setting down a railroad car which will engage with all of the trucks and wheels of a car so as to positively hold them in unaltered position and in alignment with the body of the car throughout the complete cycle of operation.

30 A further object of my invention is to provide a crane for picking up and setting down railroad cars which will work with equal rapidity, positiveness, and safety, etc., alike on all cars permitted in Interstate Commerce Commission service.

35 A further object of my invention is to provide a means for said crane which will afford maximum security against derailment or other accidents through all phases of operation.

40 A further object of my invention is to provide a mechanism which will be free from hooks, chains, or other pendulous parts which project below the horizontal plane of the lowest part of the rigid construction of the crane, after a load has been landed whereby the crane may be readily moved over the tops of cars.

45 A further object of my invention is to provide a crane which will pick up and set down a car or other load evenly.

50 A further object of my invention is to provide a crane which with its load acts as a ballistically solid mass in its reactions to

horizontally applied accelerating or decelerating forces which may be applied to the loaded crane for purposes of horizontal propulsion along the tracks of its bridge.

60

A further object of my invention is to provide a crane which will be able to accurately land its load more promptly at destination.

65 A further object of my invention is to make possible use of greatly increased rates of acceleration and deceleration in normal operation of said crane; also higher speed of crane-travel.

70 A further object of my invention is to provide a means which will increase rapidity of attachment and detachment of load by making apparatus self-adjusting.

75 A further object of my invention is to provide a crane which will be able to pick up a railroad car directly beneath the end of the car-bolster.

80 A further object of my invention is to provide a crane which can pick up a railroad car either by its bolsters or by the bottoms of its journal boxings, or by distributing the weight of said car in any desired ratio between these points of support.

85 A further object of my invention is to provide a novel construction for bridge cranes for heavy service which will increase the rigidity of the crane and will at the same time decrease the cost of its construction by permitting the insertion of rigid cross-diaphragms or diaphragm frames that connect the two main girders of the bridge 90 crane at intermediate points of the span.

95 A further object of my invention is to provide a mechanism of such nature that the operator riding on top of the bridge crane may have such complete control of his load that he can safely pick up a railroad car standing on one track under his crane and transfer the car to another track also under the crane without help from any one else, and without risk of derailing the car or 100 damaging it.

105 Other objects and advantages will appear in the following specification, and the novel features of the invention will be particularly pointed out in the appended claims.

My invention is illustrated in the accompanying drawings forming a part of this application, in which—

110 Figure 1 is an end elevation of the device, and

Figure 2 is a side elevation of the device. One form of my invention is shown in

Figures 1 and 2 and is shown handling a standard railroad box car which is to be transferred laterally from one track to another. It will be noted that this manner of suspending a load from a crane is easily adaptable for loads of any other standardized shape and I therefore do not wish to be confined to this particular shape and detail of service.

10 A plate-girder bridge 1, extends at right angles across a number of parallel railroad tracks 13, in a yard and is supported by steel brackets 2, carried by structural steel columns 3, which in turn rest on masonry bases 4. 15 is a latticed steel cross-girder at a height sufficient to clear all parts of the moving crane at all times, and is riveted to the structural columns 3 to maintain the plate girders 1 at the proper distance apart.

15 20 25 30 35 40 45 50 55 60 65 70 75 80 85 90 95 100 105 110 115 120 125 130

5 is a traveling bridge crane movable laterally on its supporting wheels 6, which rest upon track rails 7 which are fastened to top of bridge girder 1. The wheels 6 are driven by a power mechanism (not shown) and their speed is controlled by an operator riding in a cage 8 through controlling means (not shown). 9 is a box-girder frame which is a part of the traveling crane 5. 10 is a railroad track rail supported by the box-girder 9. 11 are crane trolleys carried by flanged wheels 12 which run on the rails 10. The trolleys 11 are moved by the wheels 12, these wheels being driven by mechanism (not shown); this mechanism being controlled by the operator in the cage 8. 14 are plate diaphragms strengthened by structural angles 38 and riveted to the trolleys 11. Said diaphragm plates and their strengthening angle irons project below the bottoms of girders 9 in order that they may be better used for points of attachment for an auxiliary set of lifting mechanism 20. 16 are U-shaped sections which are riveted to the face of the trolleys 11 and to the face of the diaphragm plates 14 to make vertical grooves in which pivot-carrying plates 17 may freely slide and be firmly guided. 18 are forged steel screw members which are flattened into plates at their lower ends for riveting to the face of the pivot-bearing plate 17. The screw members 18 pass through the load bearing members in the top of the trolleys 11 and receive bronze nuts 19 whose outer rims are formed into gear teeth. These nuts are rotated in unison by gearing (not shown) and driven by a power source (not shown), that is controlled by the operator in the cage 8.

20 25 30 35 40 45 50 55 60 65 70 75 80 85 90 95 100 105 110 115 120 125 130

20 are built up structural members formed of channel irons on their inner and outer faces, these channel irons being latticed together with steel straps throughout their length, but having cover plates at and near their ends. The members 20 are fashioned as may be required to fit the size of the load

(in the drawings, I have shown the load as consisting of a railroad box car) the crane is designed to handle so that they will lift the load without the load touching the sides of the members 20. The members 20 are strong enough to carry the maximum load that will ever be put upon the I-beam members 25. 21 is a slot in the upper end of the structural member 20 and receives and pivots about a pivot pin 22 which is in turn carried by the pivot bearing plate 17. 23 is a forged steel member appropriately shaped and riveted to the face of the pivot bearing plate 17 to provide an outer bearing for the pivot pin 22. 25 is an I-beam having a specially forged L-section 25' riveted to its top so that the I-beam 25 is adapted to fit as closely as desired against the sides of the car wheels 27 at the same time engaging beneath the outside of the frame 26 of the car truck to lift the car. 25 is riveted firmly to the lower end of two adjacent structural members 20 and is the load receiving member. 28 is a chain competent to carry the maximum load that will ever come upon the I-beam 25. 29 is a turnbuckle that is set in the chain 28 for adjustment of the length of the chain in such a manner that the weight of the load on the I-beam 25 will be jointly borne by the chain 28 and the structural member 20 when the crane 5 is loaded and motionless. 30 is a steel forging riveted to the pivot bearing plate 17 and forms the pivot holding upper end of the chain 28. 31 is a steel forging similar to 30 but is riveted to the cover plate at the lower end of the member 20, and forms a pivot holding lower end for the chain 28.

33 is an I-beam extending horizontally across the structure of the trolley 11 and at right angles to the crane 5 to provide tackle points for pulleys 34 and 36 through which cable 37 is threaded. Cables 37 are wound on drums (not shown) that are carried respectively on trolleys 11 and between diaphragms 14, each drum being actuated by machinery (not shown) all of the machinery being controlled by the operator in the cage 8. 35 is a pulley attached to the I-beam 25 and carries the cable 37. 32 are tension braces from the tops of the trolley frames 11, and from the top of the diaphragm structure 14 respectively to the outer ends of the I-beams 33. Arrowheads on the cable 37 show the direction of motion of the various sections as the cable is wound upon a drum (not shown). This cable raises the structure comprising members 25, 20, and 28 from the full line position into the dotted line position. The dotted lines in Figure 1 show the raised position of the principal moving parts of the load-lifting mechanism and of the load after the bronze nuts 19 have been actuated sufficiently so as to clear the car trucks from the railroad track rails. The

entire installation is now ready for the traveling crane 5 to commence horizontal movement along the rails 7. Members 38 are structural braces for the trolleys 11 and 5 the diaphragms 14.

From the foregoing description of the various parts of the device, the operation thereof may be readily understood. It is evident that when the pivoted construction 10 composed of members 25, 20, and 28 is in raised (inoperative) position shown by the dotted lines in Figure 1, the automotive crane 5 may move freely along the bridge rails 7 even through obstructions such as rail-road cars or other dropped loads are disposed immediately under the crane 5. Conversely it is evident that the crane 5 standing 15 in its open position does not obstruct the movement of the cars on the tracks 13 immediately beneath the crane 5.

It is evident that the crane 5 with the members 25, 20, and 28 in inoperative position, may move freely from any position on the bridge structure 1 to any other position 20 on the structure 1 when a car is standing on any one of the tracks 13, and that the crane 5 may be stopped in a precise position immediately above the car on the track. If now, the cable 37 be slackened away on its winding 25 drum (not shown) it is evident that the structure 25, 20, and 28 will swing downwardly and inwardly until the I-beam 25 is in the position close to the outer face of the car wheels 27 and beneath the side-frame 30 35 of the rail-car truck. Now, if chains 28 shall have been previously adjusted by use of the turnbuckles 29 to the exact length for the desired service, it is evident that the I-beam 25 will automatically come to rest with the weight of the I-beam 25 jointly borne by the chains 28 and by the structural members 20, and that the I-beam 25 will not exert any inward pressure on the car wheel 27. The I-beam 25 does not necessarily have to touch 40 the car wheels. If now the bronze screw nuts 19 be properly rotated simultaneously by the gearing (not shown) the pivot bearing plates 17 will be raised vertically in the guides 16, and the I-beams 25 will engage 45 with the bottom side of the end frame of the car truck 26 and will lift the entire car and its truck clear of the railroad track 13 and will at the same time prevent any tendency 50 of the car trucks to get out of alignment with the railroad tracks. If now the entire crane 5 be set in motion along the bridge rails 7, as by actuating its supporting 55 wheels 6, it is evident that the crane load (car 24) will not oscillate or lag appreciably, but will maintain its fixed position with 60 relation to the pivot bearing plate 17 and consequently to the entire crane 5, since the form of suspension is such that the pivot bearing plate 17, confined by immovable 65 guide members 16, cannot rotate, and the

component of inertia of the load 24 tending to retard motion of the load is instantly assumed by the chain 28 on the side of the crane 5 toward which the accelerating force is tending, and also by the structural member 20 on that side of the crane 5 away from which the accelerating force is tending. At the same time, the other structural member 20 and the other chain 28 will have their respective parts of pressure of load 24 70 temporarily reduced by like amounts as their mates are increased. When a decelerating or braking force is applied to the crane 5 to stop its motion, the suspension members prevent the pendulous oscillation 75 of the load in a similar manner except that an excess load is in that case assumed by the leading structural member 20 and by the following (rear) chain 28, while leading (forward) chain 28 and following (rear) 80 member 20 are relieved of a portion of their loadings. This shifting of the loadings from one suspension member to its mate will be instantaneous and without appreciable lateral movement of the load under the crane 85 due to the fact that all suspension members are at the time already under tension and accordingly a very slight lateral displacement of loading laterally will cause a very great proportional transference of strains from 90 one suspension member to the other.

When the crane is moved, the load carried by the crane tends to lag. In case the acceleration of the crane is too rapid, the entire weight of the load will come on the 100 forward (leading) chain and the rear (following) rigid arm 20, acting jointly. The rear chain 28 will harmlessly slacken. The forward rigid arm 20 will be under a compressive strain, unless it is permitted to move 105 upwardly, and to allow for this movement, so as to avoid damage, I have provided the slots 21 in the upper end of each structural member 20. The same safety result might be accomplished by incorporating a properly 110 designed hinge joint in the structural members 20 to relieve the compressive strains thus occurring in said members 20. An excessive decelerating (braking) force would produce a like effect but on the opposite set 115 of members and is similarly provided for. In either of the above cases this form of suspension would suffer no damage and displacement of loading would vanish almost instantly without shock when the accelerating (or decelerating) force has dropped to a magnitude less than the offsets of centers— 22 and 30—in that particular structure have provided for. Harmonic pendulum action 120 of load will not maintain in a load with this construction in practical operation. Since the load is thus held unalterably to its relative position with regard to the fixed points of the crane 5, and since the trucks and the 125 wheels of the cars are held rigidly to line 130

while the car is being lifted, transported, and landed, it is evident that when the crane 5 is brought to rest in precise agreement with a predetermined index vertically above 5 a desired track 13, the car 24 can be lowered directly upon the track 13 by properly actuating the bronze nuts 19 and thus lowering the pivot plate 17. This precise dropping of the loading of the crane 5 will occur without loss of time and with a great certainty 10 that all of the wheels of the car 24 will rest in proper running position upon the track 13.

Especial attention is called to the fact that 15 in landing a car from the crane to the track with this invention, the doubly competent weight carrying members of suspension and the load receiving member 25 are in best possible position to catch the car should the 20 wheels not be landed quite right, that the weight would in such case be caught directly by that part of the car construction which normally bears the weight and the shocks of travel, and that the displacement of the center pivot of the bolster of the car in lifting or landing the same is impossible in operation except by most gross negligence on the 25 part of the operators of the apparatus.

After the car is properly seated upon the 30 desired track, the power is applied to the drums (not shown) and the cables 37 are wound on the drums, thus raising the structural members 20, 28, and 25 to the positions shown by the dotted lines of Figure 1 and 35 the crane 5 is then free to move along the bridge structure 1 without hindrance from or damage to its lately dropped load, i. e., the car 24.

It is evident from the relative location of 40 the pivots, chains 28, and the structural members 20, that unless some special means were provided to lift the slack from the chain 28 as the structural members 20 are swung outwardly and upwardly about their 45 pivot 22, the chain 28 would sag deeply and might become seriously in the way. For this reason the end of the cable 37 is attached to a mid-point of the chain 28 and is carried through a series of pulley blocks 50 34, 35, and 36, in such a way that the cable 37 automatically lifts the sag out of the chain 28 at the same time that it lifts the members 20 and 25. It is evident that cranes of different sizes and proportions for different 55 services will require variation in number of pulleys used and in detail of threading the cables. Accordingly I desire not to be restricted to the specific detail as shown herein for accomplishing this very important 60 combined result.

It is at once evident that the hereabove 65 described method of grasping and raising objects which are to be moved by overhead movable bridge crane is readily applicable to any other standard shaped load and I do

not wish to be limited to its application to railroad cars.

In the mechanism as shown in Figure 1, both the opposed members 20 are secured to a single pivot 22. It is evidently immaterial whether these two members use a single pivot or whether they use separate pivots so long as each unit of one flexible member 28 and one structural member non-collapsible in tension 20, share the load 24 between them as above described, and so long as the upper pivots of the chain 28 and of the member 20 are rigidly confined by guide members to vertical motion over an immovable surface, and so long as both pivots of the aforesaid unit of one flexible member 28 and one structural member 20 never alter their relative positions, one from the other. My invention only requires the unchanging 85 relative position of pivots rigidly confined to vertical motion and movable as a unit. Therefore I desire not to be confined to the construction shown.

It is at once evident that the necessary 90 safety feature provided by the slotted hole 21 may be equally served by a number of mechanical expedients of which this is the preferred form in the nature of hinged joints which shall render member 20 collapsible under compression without affecting 95 its rigidity under tension. Accordingly I desire not to be confined to the slot though this is a preferred form of the construction.

It is evident that other methods of actuating the pivot bearing plate 17 in a vertical plane would serve equally as well as the screws 18 and nuts 19 shown herein; I accordingly desire not to be restricted to the particular detail as shown.

It is evident that wheels or rollers may 105 be used in place of guide slides 16 without affecting the basic end sought and accordingly I desire not to be restricted to the slides as shown, though they are the preferred 110 construction.

It is at once evident that my improvement is equally adaptable to faces of trolleys or to fixed diaphragms in traveling bridge cranes, dependent on span of crane and loads it is intended to handle. The construction as 115 shown, two movable trolleys and one pair of diaphragms, is the preferred form for a railroad switching crane of long span that is required to handle both passenger and freight equipment. It is evident that the crane might be equipped with fixed diaphragms only or with single movable trolley or with any combination thereof. Accordingly I desire not to be restricted to particular 120 construction shown.

It is at once evident that this form of 125 suspension of load from a traveling crane whereby their points of attachment are a considerable distance below the main body of the crane instead of being pivoted 130

through ropes or chains to suspension points located above the crane structure proper as in the ordinary construction of bridge cranes, makes it practical to apply power for horizontal impulses much more favorably and at lower points than is practical with the ordinary construction, and also to use more intense applications of force in accelerating and retarding the crane without giving rise to any dangerous tendency of strain that might upset the crane or set its load into dangerous or uncontrollable oscillations. This results in practicability of use of accelerating and decelerating increments of speed far greater than is practicable with other forms of construction, or employed in present practice with large cranes under heavy loads. This results also in higher traveling speed limit for the crane.

20 It will be noted from Figure 2 that the end trolleys 11 are movable, i. e., they are mounted upon the wheels 12 which are adapted to carry the trolleys along the crane.

25 5. The central lifting member, however, is not movable, but is rigidly secured to the crane 5. In this central device, the frame 14 is riveted to the crane 5 and not to the trolley frame 11 as is the case with the end trolleys. In case the freight car or other object is relatively small, the central lifting member and either one of the end members are used to lift the car from one track and dispose the car upon the desired track. In the drawing the crane is shown lifting a relatively long freight car and in this case the two end trolleys are being used. The two end members may be moved on their wheels 12 by any mechanism (not shown) so as to position these members in the desired place with respect to the railroad car.

40 I claim:

1. A traveling bridge crane comprising a support, a frame movably carried by said support, arms carried by said frame and arranged to engage with a load to lift the latter, and flexible means connecting said arms to said frame to steady the suspended load.

2. A traveling bridge crane comprising a support, a frame movably carried by said support, arms carried by said frame and arranged to engage with a load to lift the latter, and jointed means connecting said arms to said frame to steady the suspended load.

3. A traveling bridge crane comprising a support, a frame movably carried by said support, arms carried by said frame and arranged to engage with a load to lift the latter, and suspension means, yieldable under compression, for connecting said arms to said frame to steady the load.

4. A traveling crane comprising a support, a frame movable vertically on said support, arms pivotally carried by said frame for suspending a load, each of said arms

being movable, within limits, under an upwardly directed compression force.

5. A traveling crane comprising a support, a frame movable vertically on said support, arms pivotally carried by said frame for suspending a load, each of said arms being movable, within limits, under an upwardly directed compression force while the crane is carrying the load.

6. A traveling crane comprising a support, a frame movable vertically on said support, arms pivotally carried by said frame for suspending a load, each of said arms being movable within limits under an upwardly directed compression force while the crane is carrying the load, and jointed means connecting said frame with said arms for steadyng the load.

7. A traveling bridge crane comprising a support, pivoted arms arranged to suspend a load, jointed means for steadyng the load when suspended, and means for raising the arms vertically.

8. A traveling bridge crane comprising a support, pivoted arms arranged to suspend a load, jointed means for steadyng the load when suspended, and means for simultaneously raising the arms and the steadyng means, vertically.

9. In a traveling crane, a movable frame, movable member carried by said frame, means for raising and lowering said member, arms carried by said member and being adapted to engage with a car to lift the latter when said member is moved, and jointed means connecting said frame to said member to steady the load.

10. In a traveling crane, a movable frame, a plate slidably carried by said frame, means for raising and lowering said plate, arms carried by said plate and being adapted to engage with a car to lift the latter when said plate is moved, and means connecting the free ends of said arms with said plate to prevent movement of said arms toward each other when they have engaged with a load.

11. A traveling crane comprising a movable frame, plates slidably carried by said frame, means for moving said plates, arms hingedly secured to said plates, jointed means connecting said arms to said plate for steadyng the load and means for swinging said arms into inoperative position.

12. A traveling crane comprising a movable frame, plates slidably carried by said frame, pins carried by said plates, arms having slots adapted to receive said pins, whereby said arms are adapted to move so as to cause said pins to slide in said slots.

13. A traveling crane comprising a movable frame, plates slidably carried by said frame, arms pivotally carried by said plates, tension members connecting said arms to said plates, and means for swinging said

arms into inoperative position, said means also being attached to said tension members to swing said tension members into inoperative position when said arms are swung.

14. A traveling crane comprising a fixed frame and movable frames, plates carried by each frame, arms carried by each plate and adapted to be swung into a position to engage with a railroad car, said movable frame adapted to be moved toward or away from said fixed frame, and means for moving said plates whereby the car will be lifted.

15. A traveling crane comprising a support, a frame movably carried by said support, and being adapted to be moved in any direction in a given plane, arms carried by said frame and being adapted to engage with a car to lift the latter and jointed means connecting the free ends of said arms with said frame.

16. In a traveling crane, a frame, a plate slidably carried by said frame, means for raising and lowering said plate, arms carried by said plate and being adapted to engage with a car to lift the latter when said plate is moved, and means connecting the free ends of said arms with said plate to prevent movement of said arms toward each other when they have engaged with a load.

17. A traveling crane comprising a support, arms carried by said support and being adapted to engage with a railroad car to lift the latter, jointed means connecting the free ends of said arms with said support and means for swinging said jointed connections above the top of the car, when said arms are swung into inoperative position.

18. A traveling crane comprising a support, a frame carried by said support, arms secured to said frame and being adapted to engage with a railroad car to lift the latter, auxiliary frames carried by said support and being adapted to move toward or away from said first named frame, and car lifting arms carried by said auxiliary frames.

19. A traveling crane comprising a support, a frame carried by said support, pivot pins carried by said frames and car lifting arms pivotally carried by said pins, said arms having slots therein, whereby they are adapted to move slightly with respect to said pins.

20. In a traveling crane, a frame, movable members carried by said frame, arms

carried by said members, and rigid car engaging members secured to the free ends of said arms and joining said arms into pairs.

21. A traveling bridge crane comprising a frame, supports carried by said frame and arranged to engage with a load to lift the latter, and flexible means connecting said supports to said frame to steady the suspended load, said flexible means and said supports being connected together so as to prevent the swinging of said supports with respect to the frame, when said supports engage with the load.

22. A traveling bridge crane comprising a frame, supports carried by said frame and arranged to engage with a load to lift the latter, and jointed means connecting said supports to said frame to steady the suspended load, said jointed means and said supports being connected together so as to prevent the swinging of said supports with respect to the frame, when said supports engage with the load.

23. A traveling bridge crane comprising a frame, supports carried by said frame and arranged to engage with a load to lift the latter, and jointed means connecting said supports to said frame to steady the suspended load, said jointed means and said supports being connected together so as to prevent the swinging of said supports with respect to the frame, when said supports engage with the load, and means for moving said supports and jointed means above the load whereby the crane is adapted to move over the load.

24. A traveling bridge crane comprising frames adapted to be moved toward or away from each other, supports carried by said frame and arranged to engage with a load to lift the latter, and means connected to the free ends of said supports for preventing the movement of said supports relative to said frames whereby said supports and said means are adapted to steady the suspended load.

25. In a device of the type described, load engaging members, and means connected to said members adjacent to the point at which the member is engaged with the load for preventing the swinging of said members, whereby said members together with said means will steady a suspended load.

FRANK W. EAGELSTON.
